UNITED STATES PATENT OFFICE.

CAMILLE DE VLEESCHOUWER AND JOHANNES TACOMA, OF AMSTERDAM, NETHERLANDS.

DESK OR CABINET FOR DISAPPEARING TYPE-WRITING MACHINES

1,223,677.

Specification of Letters Patent. Patented Apr. 24, 1917.

Original application filed July 23, 1914, Serial No. 852,628. Divided and this application filed March 9, 1916. Serial No. 83,028.

To all whom it may concern:

Be it known that we, CAMILLE DE VLEESCHOUWER and JOHANNES TACOMA, subjects of the Queen of the Netherlands, the former residing at Amstelveensche Weg 139 and the latter residing at Nieuwe Zijds Voorburgwal 227, both in Amsterdam, in the Kingdom of the Netherlands, have invented certain new and useful Improvements in or Connected with Desks or Cabinets for Disappearing Type-Writing Machines, of which the following is a specification, reference being had to the drawings hereto annexed and to the figures and letters marked thereon—that is to say:

The present invention has reference to a desk having a typewriter mounted at the side in such a manner as to swing, in which the board supporting the typewriter is suspended in the usual manner by means of a parallelogram of rods, and the weight of the machine is entirely or partially compensated by springs.

The object of the present invention is to simplify the raising and lowering of the typewriter.

According to the present invention, this is obtained by the fact that the parallelogram-shaped guides are connected to the door of the case, in which the machine is kept when not in use, in such a manner that when the machine is raised, this door moves backward, under the supporting board of the machine into the case.

The improved device is shown in the accompanying drawings in which:—

Figure 1 shows a vertical section through the case, the machine being out of use.

Fig. 2 shows the machine in position for typing.

In Fig. 1 the typewriter is designated by 1. It rests upon the supporting board 2 which is suspended by two pairs of rods 3, 4, pivotally connected to it, in such a manner as to swing on the sides of the case. The side of the case, the supporting board 2, and the two pairs of rods 3, 4 form the well known parallelogram suspension. The springs 5 serve to compensate the weight of the typewriter. They are adjustably connected at their lower ends to the case, while their upper ends are provided with eyes 6 through which a cross bar 7 is passed, which

is connected at its ends to reciprocating levers 8. These levers 8 are pivotally mounted on fixed journals 9 and jointed at their free ends with the rods 10 which are in turn connected (at 11) to the back rods 3 of the parallelogram.

With this arrangement, given adequate tension of the springs 5, it is possible to compensate the weight of the typewriter almost fully, so that this may be raised with the least possible effort.

In addition to being attached to the connecting rods 10, the back rods 3 of the parallelogram are connected to a further system of rods by means of which the door 12 of the case is moved in such a manner, when the machine is raised, that it sinks back under the supporting board of the machine into the casing.

For this purpose, the door 12 is provided with side brackets or projections 13 with which the levers 14 are at 15 connected pivotally. These levers 14 are pivotally mounted at 16 on the casing, while their short ends 17 are connected, by means of connecting rods 18, to the rods 3 of the parallelogram at the point 19 between the fixed pivoting point of said rods 3 and the point 11 at which the connecting rods 10 of the weight compensation mechanism are jointed thereto. The joint 15 between the side brackets or projections 13 and the levers 14 is situated at a determined distance from the ends 20 of these levers 14 which ends 20 are bent laterally to form abutments 21 which come into contact with the door 12 of the case, and prevent this door from sinking down too far when opened.

Now, if the machine is in the case, that is, in the position shown in Fig. 1, the following movements are required in order to bring it into the position for use, (Fig. 2):

First the door of the case is released by pulling the door forward *e. g.* by means of the grip 22, so that the door 12 swings over by its own weight, until the door 12 comes into contact with the sloping ends 20 of the levers 14 (position 12', Fig. 1).

The supporting board 2 and the machine 1 are then lifted, by means of the handle 23, into the highest position, (shown in Fig. 2) for the accomplishment of which, only the difference between the weight of the ma-

chine and the tension of the springs 5, which are of slightly lower value, has to be overcome.

Simultaneously with this raising, the lever 14 turns about its journal 16 by the action of the pressure of the back parallelogram rod 3, transmitted to its shorter end by the connecting rod 18.

When the machine has been completely raised, the door 12 of the case is brought, by this turning of the lever 14, into the position shown in Fig. 2.

In order to fix the machine in the upper position, locking devices are provided on each side of the supporting board 2, viz. a catch or stop 24, which acts in connection with the head 41 of a corresponding lock mechanism on the post of the desk. This latch mechanism is specifically disclosed in our co-pending application, filed July 23, 1914, Serial No. 859,675, of which this is a divisional application.

The lowering of the machine causes the door 12 to automatically return in the inclined position 12' (Fig. 1) so that it may be closed by simply pressing it into its vertical position, the lock 22 at the top of the door then engaging the desk.

From the above it will be clear that for bringing the machine into the position for use and to return it into the case after use, only two very simple movements of the arm are required.

Having now particularly described and ascertained the nature of the said invention and in what manner the same is to be performed, we declare that what we claim is:

1. An article of furniture having a housing provided with an opening, a movable closure for said opening, a supporting member mounted for movement through the said opening during passage between its exteriorly disposed operative position and its inoperative position within the housing wherein it is disposed so that it can be reached only when the said closure is partially open, and means for transmitting motion from the supporting member to the said movable closure to cause the latter to be automatically withdrawn into the housing during outward movement of the supporting member, the closure being free for limited independent movement relative to the said motion transmitting means.

2. An article of furniture having a housing provided with an opening, a movable closure for said opening, a supporting member mounted for movement through the said opening during passage between its exteriorly disposed operative position and its inoperative position within the housing wherein it is disposed so that it can be reached only when the said closure is partially open, and means for transmitting motion from the supporting member to the said

movable closure to cause the latter to be automatically withdrawn into the housing during outward movement of the supporting member, said means including a lever pivoted to the housing and connected operatively with the supporting member, an arm of the lever being pivotally connected with the said closure to support the same and having a limiting extension adapted to engage the closure to permit only limited independent movement of the latter relative thereto.

3. An article of furniture having a housing provided with an opening, a movable closure for said opening, a supporting member mounted for movement through the said opening during passage between its exteriorly disposed operative position and its inoperative position within the housing wherein it is disposed so that it can be reached only when the said closure is partially open, and means for transmitting motion from the supporting member to the said movable closure to cause the latter to be automatically withdrawn into the housing during outward movement of the supporting member, said means including a lever pivoted to the housing and connected operatively with the supporting member, an arm of the lever being pivotally connected with the said closure to support the same and having a limiting extension adapted to engage the inner face of the closure at a point situated below the point of pivotal connection with the lever when the closure has been displaced slightly from its normal angular relation to the lever.

4. An article of furniture having a housing provided with an opening, a movable closure for said opening, a supporting member mounted for movement through the said opening during passage between its exteriorly disposed operative position and its inoperative position within the housing wherein it is disposed so that it can be reached only when the said closure is partially open, means for transmitting motion from the supporting member to the said movable closure to cause the latter to be automatically withdrawn into the housing during outward movement of the supporting member, the closure being free for limited independent movement relative to the said motion transmitting means and means adapted to lock the supporting member automatically upon being moved into its operative position.

5. An article of furniture having a housing provided with an opening, a movable closure for said opening, a supporting member mounted for movement through the said opening during passage between its exteriorly disposed operative position and its inoperative position within the housing, wherein it is disposed so that it can be

- reached only when the said closure is partially open, and means for transmitting motion from the supporting member to the said movable member to cause the latter to 5 be automatically withdrawn into the housing during outward movement of the supporting member, the said motion transmitting means being adapted to support the closure rigidly with respect thereto during 10 movement of the supporting member to prevent the closure from swinging into contact

with the housing, the closure being free for limited independent movement relative to the said motion transmitting means.

In testimony whereof we have hereunto 15 set our hands.

CAMILLE DE VLEESCHOUWER.
JOHANNES TACOMA.
